UNITED STATES PATENT OFFICE.

ERNEST H. HORN, OF WATERBURY, CONNECTICUT, ASSIGNOR TO WATERBURY CLOCK CO., OF WATERBURY, CONNECTICUT, A CORPORATION.

SPRING CLICK FOR TIMEPIECES.

1,416,407.

Specification of Letters Patent. Patented May 16, 1922.

Application filed September 29, 1921. Serial No. 504,069.

To all whom it may concern:

Be it known that I, ERNEST H. HORN, a citizen of the United States, residing at Waterbury, in the county of New Haven and State of Connecticut, have invented a new and useful Improvement in Spring Clicks for Timepieces; and I do hereby declare the following, when taken in connection with the accompanying drawings and the characters of reference marked thereon, to be a full, clear, and exact description of the same, and which said drawings constitute part of this application, and represent, in—

Fig. 1, a view in side elevation of the rear movement-plate of a watch provided with my improved spring-click.

Fig. 2, a view thereof in transverse section on the line 2—2 of Fig. 1.

Fig. 3, a detached view in rear elevation of the rear movement-plate and its bridge as stripped.

Fig. 4, a perspective view on an enlarged scale of the spring-click.

Fig. 5, a broken sectional view on the line 5—5 of Fig. 1.

Fig. 6, a similar view on the line 6—6 of Fig. 1.

My invention relates to an improvement in spring-clicks for time-pieces of the class in which a single piece of resilient metal is adapted in form and installation to function as a click and as a spring therefor, the object of my present invention being to produce a simple and convenient click of the character described, constructed with particular reference to avoiding the stripping of the teeth of the spring-barrel, in case the main-spring breaks, and to permitting sufficient recoil of the main-spring after full winding, and to prevent the coils of the spring from sticking together when wound to the limit.

With these ends in view, my invention consists in a spring-click having certain details of construction as will be hereinafter described and pointed out in the claims.

In carrying out my invention, as herein shown, I employ a combined click and click-spring made of a single piece of tempered steel bent at one side of its longitudinal center so as to form a spring-arm 7 and a click-arm 8 standing at an obtuse angle with respect to each other. The arm 7 is provided, upon its inner edge, with a bearing-shoulder 9, from which a positioning-lug 10 offsets,

while the arm 8 is formed, upon its end, with a banking-lug 11, the effect of which is to broaden the end 12 of the said arm to the full width of the teeth 13 of the spring-barrel 14, which houses the main-spring 15. 60 The said banking-lug 11 extends into a banking-notch 16 formed in the rear movement-plate 17 of the time-piece, the said notch being so located that the lug 11 engages with its lower wall under predetermined conditions, as will be described later on.

The said combined part is mounted by the insertion of the free end of its arm 7 into the slot 18 of a bifurcated rivet 19 mounted 70 in the rear movement-plate 17, as shown in Figures 1 and 6. The shoulder 9 of the arm 7 then rests upon the inner face of the movement-plate, while the positioning-lug 10, offsetting from the said shoulder, extends sufficiently into a hole 20 formed in the plate for the reception of the rivet, to prevent the endwise movement of the arm 7 therein, but I do not limit myself to any particular manner of mounting the combined, one-piece 75 click and click-spring upon the movement-plate.

For supporting my improved combined part and springing it in the direction in which it acts as a "safety" for the spring-barrel and spring, as will be described, I employ a stud 21 riveted in the plate 17 and formed with a head 22, the said stud being a trifle longer than the width of the stock used in making the combined part. This stud 85 is positioned in the plate so as to virtually set within the bend of the combined part, as shown in Figure 1, so that the combined part is sprung by the stud 21, acting as a fulcrum, when back-pressure is thrown upon it by the 90 effort of the main-spring to unwind, but the head 22 of the stud acts, at all times, to hold the combined part in place.

During the winding or counter-clockwise rotation of the spring-barrel 14, the combined part is sprung bodily away from the stud 21 nearly throughout its length, the end 12 of the arm 8 of the said part riding easily over the teeth 13 of the spring-barrel, for the reason that the stud, by its location, 100 permits the combined part to yield from the end 12 to the rivet 19 and, therefore, nearly throughout its length, as stated. On the other hand, the moment winding pressure is removed from the main-spring 15, the barrel 105 110

14 turns in the clockwise direction and one of its teeth engages with the end 12 of the click-arm 8, so as to impose pressure thereupon, whereby the said combined part is 5 pulled downward, as it were, until the said part rests at its point 23 (Figure 4) directly upon the stud 21. The said pressure being continued, the combined part is now sprung nearly throughout its length over the said 10 stud, which acts as a fulcrum for it, and thus provides a yielding check for the clockwise movement of the spring-barrel 14. This yielding check continues in force until the banking-lug 11 is brought into engagement 15 with the lower edge of the banking-notch 16, when the counter-clockwise movement of the barrel is brought to a positive stop. I thus provide for a limited clockwise turning of the spring-barrel after the 20 spring has been fully wound, preventing the sticking of the coils of the spring together, as sometimes occurs when the spring is fully wound and when there is no provision made to permit it to slightly uncoil and so annul 25 the tendency of its coils to adhere together. Furthermore, the stripping of the teeth of the barrel, in case the main-spring breaks, is prevented by the cushioning action of the combined part, due to the springing of the 30 same over the stud 21 in the manner described.

I claim:

1. As a new article of manufacture, a combined, one-piece click and click-spring for 35 time-pieces, bent between its ends to form a click-arm and spring-arm which stand at an angle with respect to each other; in combination with means for rigidly mounting the said part by the outer end of its spring-arm.
2. In a spring-click for time-pieces, the combination with a one-piece, combined part bent between its ends to form a click-arm and a spring-arm which stand at an angle 45 with respect to each other, of a supporting rivet located in the bend of the said part, whereby the same is sprung between its ends when moved in one direction and left free to spring bodily in the opposite direction.
3. In a time-piece, the combination with 50 a movement-plate thereof, of a spring-barrel, a main-spring housed therein, a combined, one-piece click and click-spring bent between its ends to form a click-arm and a 55 spring-arm, means mounted in the said plate for supporting the said part by its spring-arm, and a supporting-rivet mounted

in the said plate within the bend of the said part, whereby the said part is sprung between its ends in the unwinding effort of the 60 barrel.

4. In a time-piece, the combination with a movement-plate having a banking-notch, of a spring-barrel, a main-spring therein, a combined, one-piece click and click-spring 65 bent between its ends and provided at its click end with a banking-lug entering the said banking-notch, means for mounting the said part in the said plate by its spring end, and a supporting-rivet located within the 70 bend of the part, whereby the springing of the said part between its ends by the said stud yieldingly checks the unwinding effort of the barrel, and whereby the banking-lug of the said part coacts with the said notch 75 and positively stops the said movement of the barrel.

5. In a time-piece, the combination with a spring-barrel, of a one-piece, combined click and click-spring bent between its ends 80 to form a click-arm and a spring-arm, which stand at an angle with respect to each other, a banking-lug located upon the said click-arm, an abutment positioned to be engaged by the said lug after the said part has been 85 sprung between its ends, and a fulcrum engaged by the said part which it springs between its ends before the said lug and abutment coact to stop the unwinding effort of the 90 said barrel.

6. In a time-piece, the combination with a movement-plate having a banking-notch, of a spring-barrel, a spring therein, a one-piece, combined click and click-spring bent 95 between its ends and provided at its click-end with a banking-lug coacting with the said notch, means for mounting the spring by its spring-end, and a supporting-rivet provided with an overhanging head for preventing the lateral displacement of the said part, and positioned in the said plate to set in the bend of the said part, which it springs between its ends to yieldingly check the reverse rotation of the said barrel, prior to the positive stopping thereof by the co-action 100 of the banking-lug and notch.

In testimony whereof, I have signed this specification in the presence of two subscribing witnesses.

ERNEST H. HORN.
